DESIGN FOR A COMBINATION BATTERY ANALYZER AND CHARGER CASING

Lee Hunter, Jr., University City, Mo.

Application August 23, 1940, Serial No. 94,589

Term of patent 7 years

To all whom it may concern:

Be it known that I, Lee Hunter, Jr., a citizen of the United States, residing in University City, St. Louis County, State of Missouri, have invented a new, original, and ornamental Design for a Combination Battery Analyzer and Charger Casing, of which the following is a specification, reference being had to the accompanying drawing forming part thereof, in which—

Fig. 1 is a top plan view of a combination battery analyzer and charger casing incorporating my novel design;

Fig. 2 is a side elevational view of the casing;

Fig. 3 is an elevational view of one end of the casing; and,

Fig. 4 is an elevational view of the other end of the casing.

The characteristic features of my design reside in the portions above the horizontal plane passing through the handle member.

I claim:

The ornamental design for a combination battery analyzer and charger casing, as shown and described.

LEE HUNTER, JR.
